W. L. McLEAN.
SCREW DRIVER.
APPLICATION FILED MAY 24, 1920.

Patented May 9, 1922.

INVENTOR,
Warren L. McLean,
BY Chas. E. Townsend
ATTORNEY

UNITED STATES PATENT OFFICE.

WARREN L. MCLEAN, OF SAN FRANCISCO, CALIFORNIA.

SCREW DRIVER.

1,415,251.

Specification of Letters Patent. Patented May 9, 1922.

Application filed May 24, 1920. Serial No. 333,617.

To all whom it may concern:

Be it known that I, WARREN L. MCLEAN, a citizen of the United States, residing at the city and county of San Francisco and State of California, have invented a new and useful Improvement in Screw Drivers, of which the following is a specification.

This invention relates to a screw driver and especially to a screw driver of the mechanical or spiral shaft actuated type.

One of the objects of the present invention is to provide a simple, substantial, cheaply manufactured screw driver in which rotary movement is transmitted to the bit or chuck by means of a spiral shaped shaft and a nut co-operating therewith.

Another object of the invention is to provide a novel form of handle and casing for the support and reception of the spiral shaft and into which it is adapted to move telescope-wise and in conjunction therewith a spring and plunger so arranged as to normally project and rotate the spiral shaft with relation to the handle, the casing and nut.

Another object of the invention is to provide a manually operated mechanism for locking the spiral shaft against projection with relation to the handle and casing when the tool is not in use.

Further objects will hereinafter appear. The invention consists of the parts and the construction, combination and arrangement of parts as hereinafter more fully described and claimed, having reference to the accompanying drawings, in which—

Fig. 1 is a side elevation of the screw driver showing the spiral shaft projected.

Fig. 2 is a central vertical longitudinal section of the screw driver showing the spiral shaft in retracted position within the casing.

Fig. 3 is a detail perspective view of the locking mechanism whereby the spiral shaft is secured against projection.

Fig. 4 is a detail view of the locking mechanism showing the spiral shaft retracted and locked against projection.

Fig. 5 is a cross section on line 5—5, Fig. 2.

Referring to the drawings in detail, A indicates a tubular casing on the upper end of which is secured a handle 2. Formed a short distance below the handle on the tube A is an annular shoulder 3, and turnably mounted on the tube between the shoulder 55 and the end of the handle 2 is a collar 4.

Suitably secured in the lower end of the tube is a nut 5, in which is formed a square opening 6, and adapted to enter the tube and pass through the opening in the nut 5 is a spiral shaped shaft 7, on the inner end of which is secured a plunger 8. Forming a closure for the upper end of the tube is a plug 9 and extending through the handle, the tube and the plug is a locking pin 10. This pin serves two functions, first that of securing the plug 9, and secondly that of securing the handle 2, both against endwise and turning movement upon the tube A. Interposed between the plug and the plunger 8 is a spring 11. This spring is provided for the purpose of normally exerting an endwise pressure on the plunger 8 and the spiral shaft 7, the spring being sufficiently long and having sufficient tension to normally project the spiral shaft as shown in Fig. 1. Secured on the lower end of the spiral shaft 7 is a standard form of screw chuck 12, which is provided for the reception of a screw driving bit, a drill or whatever tool may be employed.

Turnably mounted on the lower end of the tube is a locking collar 14. This collar is slotted near its upper end as at 15 and a pin 16 projecting therethrough secures the collar against endwise movement upon the tube and also limits the turning movement of the collar with relation thereto. Formed on the lower end of the collar is an annular in-turned shoulder 17, a portion of which is cut away, as at 18, to permit a pin 19 to pass therethrough. This pin is secured on the lower end of the spiral shaft at a point adjacent the chuck and is provided for the purpose of engaging the locking collar 14 and thereby securing the spiral shaft against projection when the tool is not in operation.

In actual operation with a bit or drill secured in the chuck 12, it is possible to impart a rotary movement thereto by first projecting the spiral shaft 7. This is accomplished by turning the collar 14 until the recess 18 registers with the pin 19. This causes a release of the locking collar with relation to the pin 19, and thereby permits projection of the spiral shaft as this is normally subjected to the pressure or endwise thrust of the spring 11.

The tool held by the chuck 12, for instance a screw driving bit, is next brought into engagement with the screw to be inserted and the chuck 12 is simultaneously held loosely

in one hand while a downward pressure is exerted on the handle 2 by the other handle. This pressure causes the tube A, the handle 2 and the nut 6, secured in the tube, to travel 5 downwardly on the spiral shaft, and as the handle, the tube and the nut is secured in the hand against rotary movement, it is obvious that a rotary movement will be transmitted to the spiral shaft, the chuck 12 and 10 the screw bit carried thereby, the spring 11 being at the same time compressed. One or two revolutions is in this manner transmitted to the screw driving bit and it is of course necessary to impart several additional 15 revolutions before the screw is driven home. It is therefore necessary to return the tube, the nut and the handle to the raised position shown in Fig. 1 so that a second downward movement may be transmitted thereto. 20 This is accomplished by grasping the chuck 12 and thereby securing the spiral shaft against rotation, and simultaneously grasping the collar 4, which is turnably mounted on the tube. The downward pressure exerted by the operator is now released and the 25 nut, the tube and the handle is permitted to be raised by the action of the spring 11. The handle, the tube and the nut will now rotate as they are only held by the collar 4 and the 30 chuck and spiral shaft are held against rotation by the other hand. In other words the tube and handle freely rotate within the hand of the operator during the upward movement of the same, but are tightly 35 grasped and held against rotation during the downward movement as it is then desired to impart a rotary movement to the spiral shaft, the chuck and the tool carried thereby. This cycle of operation is repeated as many 40 times as is necessary or until the screw is driven home.

From the foregoing it can be seen that the spiral shaft, the chuck and the tool carried thereby are automatically projected with relation to the tube and the handle, and that 45 rotary movement is simultaneously transmitted thereto by the nut 6. Again it may be stated that during the operation of the tool, the spring serves the function of automatically raising the nut, the tube and the 50 handle to return the same to working position as turning movement should only be transmitted to the shaft 7 during downward movement of the nut.

If the screw driver is to be placed in a tool box, or otherwise disposed of when not in use, it is obvious that shortening of the screw driver as a whole would be convenient

as considerable less space would be occupied. I have for this reason provided the locking 60 nut shown at 14 and the pin 19. This permits the spiral shaft to be retracted with relation to the tube, or to be moved telescope-wise within the same until the pin 19 passes through the slot 18. It is here secured by 65 merely turning the collar until the pin 16 engages the opposite end of the slot 15. The shoulder 17 on the locking collar will during this turning movement pass in under the pin 19 and will thereby secure it, together 70 with the spiral shaft, against projection. Conversely reverse movement of the collar 14 brings the slot 18 into register with the pin 19 and thereby permits the spring 11 to automatically and instantly 75 project the spiral shaft and chuck carried thereby.

While certain features of the present invention are more or less specifically illustrated, I wish it understood that various 80 changes in form and proportion may be resorted to within the scope of the appended claims, similarly that the materials and finish of the several parts employed may be such as the experience and judgment of the 85 manufacturer may dictate or varying conditions may demand.

Having thus described my invention, what I claim and desire to secure by Letters Patent is—

1. In a screw driver of the character described the combination with a spiral tool shank, a tube casing having a threaded connection with the shank to rotate the same by relative endwise movement and a handle secured to the tube of an annular shoulder formed on the tube below the handle and a collar turnably mounted on the tube between said shoulder and the handle. 95

2. In a screw driver of the character described the combination with a spiral tool shank, a tube casing having a threaded connection with the shank to rotate the same by relative endwise movement and a handle secured to the tube, of a collar turnably mounted on the casing below the handle and means securing said collar against endwise movement upon the tube. 100

In testimony whereof I have hereunto set my hand in the presence of two subscribing witnesses. 105

WARREN L. McLEAN.
